US0D1049086S

(12) **United States Design Patent** (10) **Patent No.:** **US D1,049,086 S**
(45) **Date of Patent:** **** Oct. 29, 2024**

(54) **CASE FOR AN ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, Vienna (AT); **Clement Tissandier**, San Francisco, CA (US); **Eugene Antony Whang**, San Francisco, CA (US); **Rico Zörkendöfer**, San Francisco, CA (US)

(73) Assignee: **Apple Inc.**, Cupertino, CA (US)

(**) Term: **15 Years**

(21) Appl. No.: **29/867,937**

(22) Filed: **Nov. 14, 2022**

CLAIM

The ornamental design for a case for an electronic device as shown and described.

DESCRIPTION

FIG. 1 is a bottom front perspective view of a case for an electronic device showing the claimed design;

FIG. 2 is a top front perspective view thereof;

FIG. 3 is a bottom rear perspective view thereof;

FIG. 4 is a top rear perspective view thereof;

FIG. 5 is a front view thereof;

FIG. 6 is a rear view thereof;

(Continued)

FIG. 7 is a left side view thereof;
 FIG. 8 is a right side view thereof;
 FIG. 9 is a top view thereof; and,
 FIG. 10 is a bottom view thereof.
 The broken lines in the figures show portions of the case for
 an electronic device that form no part of the claimed design.

1 Claim, 8 Drawing Sheets

Related U.S. Application Data

continuation of application No. 29/655,330, filed on
 Jul. 2, 2018, now Pat. No. Des. 926,739.
